UNITED STATES PATENT OFFICE.

IRA E. DAVENPORT, OF MECHANICSVILLE, VERMONT.

SLED-BRAKE.

SPECIFICATION forming part of Letters Patent No. 234,252, dated November 9, 1880.

Application filed September 18, 1880. (Model.)

To all whom it may concern:

Be it known that I, IRA E. DAVENPORT, of Mechanicsville, in the county of Rutland and State of Vermont, have invented a new and useful Improvement in Sled-Brakes, of which the following is a specification.

My invention relates to a brake for bobsleighs; and it consists in a novel arrangement of levers and devices connected therewith, whereby the brakes are applied to the front sled by the momentum of the rear sled when the speed of the team is checked or when holding back in going downhill.

In the accompanying drawings, Figure 1 is a bottom view of a bob-sleigh provided with my improvements. Fig. 2 is a longitudinal vertical sectional view of the same.

Similar letters of reference indicate corresponding parts.

A represents the front sled, and B the rear one. A² is the front bolster, and B² the rear one, which are connected by two reaches, C C. The rear bolster is connected to the raves b b of the rear sled by hinge or eye joints c c. The front bolster is connected by a bolt, d, to a board, E, which lies parallel with the runners of the front sled and rests on the beams a a² a³, which connect said runners. Near the ends of the board E are slots e e, in which work bolts D D, projecting upward from the beams a and a³, and said board is held down to its place by two clips, f f, passing into said beams a a³. The board is thus allowed to slide longitudinally on the beams without being dis- placed upward. In order to prevent too much wear of the contiguous surfaces, they may be faced with metal plates g.

H H are two eyebolts, which project forward from the middle beam, a², and form the fulcra for two levers, J J, which extend laterally toward the runners. One arm of each lever J is pivoted to the under side of the board E, and the other arm is connected by a rod, K, with one arm of a vertical elbow-lever, L, having its fulcrum on the inner side of the sled-runner, and having its other arm terminating in a dog, l, which constitutes the brake.

When the speed of the team is slackened or when holding back in descending a hill the momentum of the rear sled, B, acting through the reaches C C and sliding board E, causes a forward movement of the long arms of the levers J J, a backward movement of their short arms and of the long arms of the elbow-levers L L, and a downward movement of the short arms of said levers L L, so as to cause the dogs l to catch in the road and thus brake the sled.

Having thus described my invention, I claim as new and desire to secure by Letters Patent—

A sled-brake attached to the front sled of a bob-sleigh, consisting of elbow-levers L, provided with dogs l, and connected with a longitudinally-sliding board, E, actuated by the momentum of the rear sled through the bolsters and reaches connecting said front and rear sleds, substantially as herein described.

IRA ELIJAH DAVENPORT.
